CLOCK FACE OR THE LIKE

Stephen P. Opert, 952 Richmond Road,
East Meadow, N.Y. 11554

Filed June 14, 1972, Ser. No. 262,721

Term of patent 14 years

Int. Cl. D10—07

U.S. Cl. D10—123

FIG. 1

FIG. 3

FIG. 2

FIG. 4

FIG. 1 is a top plan view of a clock face or the like showing my new design;

FIG. 2 is a side elevational view thereof;

FIG. 3 is a top plan view of another embodiment of my new design of FIGS. 1 and 2;

FIG. 4 is a top plan view of yet another embodiment of my new design of FIGS. 1 and 2.

I claim:

The ornamental design for a clock face or the like, as shown and described.
